US00D527000S

(12) **United States Design Patent** (10) **Patent No.:** **US D527,000 S**
Hong et al. (45) **Date of Patent:** **** Aug. 22, 2006**

(54) **PERSONAL DIGITAL ASSISTANT**

(75) Inventors: **Sung-Hoon Hong**, Suwon-si (KR);
Jong-Seong Lee, Seoul (KR); **Yang-Jic Lee**, Seoul (KR)

(73) Assignee: **Samsung Electronics Co., Ltd.** (KR)

(**) Term: **14 Years**

(21) Appl. No.: **29/217,188**

(22) Filed: **Nov. 15, 2004**

(30) **Foreign Application Priority Data**

Jun. 10, 2004 (KR) 30-2004-0017378

(51) **LOC (8) CI.** **14-02**

(52) **U.S. CI.** **D14/346**; D14/138

(57) **CLAIM**

We claim, the ornamental design for a personal digital assistant, as shown and described.

DESCRIPTION

FIG. 1 is a top and front perspective view of a personal digital assistant, showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top elevational view thereof;
FIG. 7 is a bottom elevational view thereof; and,
FIG. 8 is a front perspective view thereof, showing the personal digital assistant in an alternate position.
